UNITED STATES PATENT OFFICE.

ART GUSTAFSON, OF MOLINE, ILLINOIS.

FOLDING UMBRELLA.

1,353,234.

Specification of Letters Patent. Patented Sept. 21, 1920.

Application filed November 22, 1919. Serial No. 339,918.

To all whom it may concern:

Be it known that I, ART GUSTAFSON, a citizen of the United States, residing at Moline, in the county of Rock Island and State 5 of Illinois, have invented certain new and useful Improvements in Folding Umbrellas, of which the following is a specification.

This invention relates to umbrellas and more particularly to folding umbrellas.

10 The object of the invention is to provide a simple and cheaply constructed article of this character which may be quickly opened or closed by sliding a sleeve on the stick in the usual manner.

15 Another object is to construct such an article with a folding frame and a telescopic stick so that it will occupy a minimum amount of space when collapsed, yet be quickly and easily opened for use.

20 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

30 In the accompanying drawings:

Figure 1 represents a side elevation partly in section of an umbrella frame constructed in accordance with this invention shown in open position.

35 Fig. 2 is a similar view of the frame shown in collapsed folded position, parts being broken out for convenience and illustration.

Fig. 3 is a detail side elevation showing 40 the connection of the rib sections with each other and with one of the braces.

Fig. 4 is a bottom plan view thereof.

Fig. 5 is a transverse section taken on the line 5—5 of Fig. 1.

45 Fig. 6 is a similar view taken on the line 6—6 of Fig. 1.

Fig. 7 is a detail side elevation of a portion of one of the ribs: and

Fig. 8 is a bottom plan view thereof.

50 In the embodiment illustrated the umbrella stick 1 is shown composed of a tubular inner section 2 in which is designed to slide an outer section 6 which is held in extended open position by a spring pressed catch 8 mounted in a recess 7 in the member 6 and which is designed when the stick is extended

to engage in aperture 2^a in the member 2 as is shown clearly in Fig. 6.

The lower end of the section 6 is enlarged as shown at 9 and provided at its free end 60 with a hand grip in the form of a knob 10, a shoulder 11 being formed at the inner end of the enlarged portion 9 and which is designed to engage the end of tube 2 when the sections are in telescoped closed position. 65

Carried by the tubular portion 2 of the stick is a collar 4 mounted on the solid end 3 of said section 2 and having radially extending apertured lugs or ears 5 with which are pivotally engaged the inner sections 13 70 of the folding ribs 12. These ribs 12 are composed of two sections 13 and 14 pivotally connected at their meeting ends as shown at 15, the inner end of the outer section 14 of each rib having an extension 17 which carries apertured ears on its outer face to receive the outer end of section 13 which is pivotally connected at this point, a spring 16 operating to hold said sections in open position as is shown clearly in Figs. 1 and 3. 80 The extension 17 of section 14 carries at its free end a pivoted arm 18 which is bifurcated and the furcations 18^a thereof straddle the brace 20 which connects section 13 with a sliding sleeve 25 mounted on the tubular 85 stick section 2. A roller 19 is carried by the outer or free ends of the furcations 18^a and bears on the inner edge of brace 20, a spring 21 operating to hold said member 18 in operative position. 90

Mounted to slide on each rib section 13 is a sleeve 22 pivotally connected with the outer end of brace 20 and which carries a spring tongue 24 designed to enter a dent 23 in the inner edge of rib section 13, to prevent said sleeve from sliding too loosely on the rib section and yet permit it to move rearwardly when the frame is to be collapsed. 95

The sleeve 25 which slides on stick section 100 2 carries a spring catch 26 designed to lock said sleeve in raised or lowered position and this sleeve carries the brace members 20 which connect with the rib sections 13, said braces being pivotally connected with said 105 sleeve.

Section 2 of the stick is shown provided near its upper end with a laterally extending lug 2^a to form a stop for limiting the upward movement of sleeve 25 and said member 2 is provided at a point spaced inwardly from stop 2^a with an aperture 2^b designed 110

to receive catch 26 for locking sleeve 25 in raised position. This member 2 is also provided near its lower end with another aperture 2° which is designed to receive the catch 8 carried by the inner end of section 6 for locking the stick sections in extended position.

In the use of this umbrella, it being of course understood that the frame is covered 10 with the ordinary cloth attached to the collar 4 and to the free ends of the stick sections 14, when it is desired to fold up the umbrella the catch 26 is released from aperture 2° and the sleeve 25 moved downwardly on 15 tubular stick section 2 which movement causes the sleeves 22 to slide inwardly on the rib sections 13 thereby exerting a pull on the links or arms 18 which operates to fold the outer rib sections 14 inwardly on 20 the outer face of sections 13 in the position shown in Fig. 2. When the frame has been so collapsed section 6 of the stick is disengaged from section 2 by depressing catch 8 and said section is moved inwardly until 25 the shoulder 11 contacts with the outer end of tube 2 in which position it will be held by catch 26 bearing on section 6 as is shown clearly in Fig. 2.

To open the umbrella, catch 26 is depressed to release it from section 6, the hand grip 10 grasped and pulled outwardly until catch 8 engages with recess 2° when the stick will be in open position ready for use. Sleeve 25 is then moved upwardly on the 30 stick section 2 which causes the rib sections 14 to open outwardly owing to the outward sliding movement of the sleeves 22 on rib sections 13 and when they reach the position shown in Fig. 1 they will be securely 35 held by the springs 16 and 21 and the umbrella is ready for use.

From the foregoing description, taken in connection with the accompanying drawings, the advantages of the construction and 40 of the method of operation will be readily apparent to those skilled in the art to which the invention appertains and while I have described the principle of operation of the

invention together with the device which I now consider to be the best embodiment 50 thereof, I desire to have it understood that the device shown is merely illustrative and that such changes may be made as are within the scope of the claimed invention.

Having thus fully described my invention, 55 what I claim as new and desire to secure by Letters Patent, is:

1. A folding umbrella comprising a stick, a sleeve slidable on said stick, ribs pivoted at one end to the upper end of said stick 60 and each composed of two sections hingedly connected at their meeting ends, a spring for normally holding said sections in open position, sleeves slidable on the inner rib section, brace rods connecting said sleeve on 65 the stick with the sleeves on the rib sections, arms carried by the outer rib sections at the rear of their pivotal connection, said arms carrying rollers engaged with the inner edges of said brace rods whereby the raising 70 and lowering of the sleeve on the stick will operate to open and close the outer and inner rib sections.

2. A folding umbrella comprising a stick, a sleeve slidable on said stick, ribs pivoted 75 at one end to the upper end of said stick and each composed of two sections hingedly connected at their meeting ends, a spring for normally holding said sections in open position, sleeves slidable on the inner rib 80 sections, brace rods connecting said sleeve on the stick with those on the rib sections, bifurcated arms carried by the outer rib sections at the rear of their pivotal connection, 85 said arms straddling said brace rods and carrying rollers engaged with the inner edges thereof, whereby the raising and lowering of the sleeve on the stick will operate to open and close the outer and inner rib sections.

In testimony whereof I affix my signature in presence of two witnesses.

ART GUSTAFSON.
